DOWNDRAFT DIVERTER

Filed March 19, 1949

UNITED STATES PATENT OFFICE

2,660,998

DOWNDRAFT DIVERTER

Richard E. James and Albert J. Lampert, Los Angeles, Calif., assignors to Rheem Manufacturing Company, Richmond, Calif., a corporation of California

Application March 19, 1949, Serial No. 82,386

4 Claims. (Cl. 126—307)

1

Our invention relates to gas burning equipment and has particular reference to a new and improved downdraft diverter adapted to prevent any drafts which may be forced downwardly in the exhaust stack from being communicated to the gas burner head, which would result in extinguishment thereof or in the contamination of the quarters in which the equipment is located with the products of combustion from the gas burner.

We are aware that the downdraft diverter art is quite crowded and that a great many diverters have been developed. However, it is among the objects of our invention to provide a more efficient downdraft diverter and, particularly, a downdraft diverter which can be installed in relatively shallow places.

Previous attempts to produce downdraft diverters for installation on gas burning equipment wherein relatively shallow spaces are available have resulted in failure, in that such downdraft diverters have permitted spillage of products of combustion around the outer periphery thereof.

It is also among the objects of our invention to provide a relatively shallow downdraft diverter, which due to its double-walled construction substantially eliminates any spillage of the products of combustion, and yet which permits the free exit of the products of combustion and at the same time prevents or diverts downdraft currents from reaching the combustion chamber, which downdraft currents may and often do result in extinguishing the gas flame.

Downdraft diverters as heretofore known in the art have been constructed with diverter cones having substantially the same diameter as the exhaust flue and stack. Such construction materially interferes with the movement of products of combustion out the exhaust stack unless sufficient spacing is provided between the flue and the diverter and the diverter and the exhaust stack. This type of downdraft diverter is of necessity relatively high in construction.

It is further among the objects of our invention to provide a downdraft diverter having a relatively small diverter cone which will effectively prevent the return of downdrafts into the combustion chamber and will not interfere materially with the upward course of products of combustion.

Other and further objects and advantages of our invention will become apparent from the drawings and the specifications relative thereto.

In the drawings:

Figure 1 is a side elevation of a downdraft 55 It extends the flue 33 upwardly to a point slightly

2

diverter embodying the principles of our invention.

Figure 2 is a bottom plan view of our downdraft diverter taken on line 2—2 of Figure 1.

Figure 3 is a sectional view taken on line 3—3 of Figure 1.

Figure 4 is a perspective view of the means for supporting the hood on a mounting collar.

Our invention is composed primarily of four 10 parts, namely, the outer hood designated generally 10, an inner ring 11 supported by said hood, a diverter cone 12, and a mounting collar 13.

The outer hood 10 is generally dome-shaped 15 having a generally concave undersurface and an upwardly extending flange 15, said flange defining an aperture to permit the exit of products of combustion.

The lower limit of the hood 10 is defined by a 20 downwardly extending lip 16 lying in a common plane and is formed with diametrically opposed, semi-circular indentations 17 and 18. The indentations 17 and 18 are to permit the passage of water pipes in such appliances as water heaters. The purpose of such construction is so that 25 a downdraft diverter embodying the principles of our invention, which is relatively wide and shallow, can be installed on standard domestic water heaters.

The upper periphery of the collar 13 should 30 be approximately in a common plane with the lip 16 or slightly above it.

The inner ring 11 is formed with a cylindrical 35 wall 20 and an inwardly directed peripheral flange 21 disposed about the upper edge of the cylindrical wall 20. The flange 21 is securely fastened to the hood 10 by means of spot welding or the like.

The lower edge of the cylindrical wall 20 is 40 formed with an outwardly directed lip 22 terminating in a common plane above the plane of the hood lip 16. The inner ring 11 being of substantially less diameter than the outer hood 10 defines an annular chamber 24 open at the bottom, and which is bounded by the ring 11 and the outer portion of the hood 10.

The diverter cone is generally conically shaped and has a diameter substantially less than the diameter of the mounting collar 13 and the passage defined by the annular flange 15. The diverter cone is positioned with its apex pointing upwardly and is co-axial with the mounting collar 13 and the annular flange 15.

The mounting collar 13 serves a dual function.

above the hood lip 16 and provides means for centering and securing the downdraft diverter to a water heater. Other means of performing these functions, such as disposing the legs 31 directly onto the flue 33 so that the flue 33 itself extends slightly above the lip 16, should be considered within the scope of our invention.

The diverter cone is formed with a plurality of upwardly extending legs 30 adapted to be secured to the inner surface of the annular collar 15 by any suitable means, such as spot welding.

The cone 12 is also formed with a plurality of downwardly extending legs 31, each of which is formed with an outwardly directed ridge 32. The legs 31 are inserted into the mounting collar 13 until the ridges 32 abut against the upper edge of the ring 13 and the legs 31 are then secured to the ring 13 by such means as spot welding:

By the construction above described, we have been able to produce a downdraft diverter which can be installed in relatively shallow spaces, and yet which effectively prevents harmful downdrafts or spillage of the products of combustion.

In the upward course of products of combustion through an exhaust stack, such as 33, the gases effectively by-pass the diverter cone 12 and pass upwardly through the stack 34. In the event of a downdraft, the cone 12 diverts the gases outwardly so that they are directed beyond the periphery of the mounting sleeve 13 or the flue 33, which prevents communication with the combustion chamber thereby protecting the gas burner.

While gases are passing upwardly, a stream of fresh air is induced to flow upwardly in the annular space defined between the lip 22 of the inner ring and the periphery of the collar 13. In the event of a momentary stoppage of the gases flowing upwardly due to such causes as momentary gusts of wind, the products of combustion will first fill the inner chamber defined by the ring 11 and may then spill over into the annular chamber 24, thereby preventing spillage of the products of combustion into the room or quarters where the equipment is being used.

While we have herein shown and described our invention in what we have conceived to be the most practical and preferred embodiment, it is recognized that departures may be made therefrom within the scope of our invention, which is not to be limited to the details disclosed herein, but is to be accorded the full scope of the claims so as to embrace any and all equivalent devices.

Having described our invention, what we claim as new and desire to secure by Letters Patent is:

1. A shallow-type downdraft diverter comprising a relatively shallow dome-shaped hood being open at the bottom having an aperture at the top adapted to communicate with a vent for the passage of products of combustion, a cone-shaped substantially circular diverter in spaced relation and subjacent said hood aperture, the diameter of the diverter being substantially less than the diameter of said aperture, and an annular flange depending from, and the upper edge thereof being in intimate contact with said hood, the diameter of said flange being greater than the diameter of said hood aperture and less than the diameter of the lower edge of the hood and the lower edge of the flange being disposed above the lower edge of said hood, said hood aperture, said diverter and said annular flange being in coaxial relation, a passage for products of combustion being thereby formed between the di-

verter and the flange and thence upwardly through the aperture in the top of the hood.

2. A shallow-type downdraft diverter comprising a relatively shallow dome-shaped hood having an aperture at the top adapted to communicate with a vent, a cone-shaped substantially circular diverter having its apex directed upwardly suspended co-axially below said top opening, the diameter of the diverter being substantially less than the diameter of said aperture, said diverter being located approximately midway between the top and lower edges of the hood, and an annular flange depending from, and the upper edge thereof being in intimate and co-axial contact with said hood, the diameter of said flange being greater than the diameter of said hood aperture and less than the diameter of the lower edge of the hood, and the lower edge of the flange being disposed above the lower edge of said hood, a passage for products of combustion being thereby formed between the diverter and the flange and thence upwardly through the aperture in the top of the hood, and primary and secondary pockets for downdraft condition being formed, the primary downdraft pocket being defined by the flange and the superadjacent wall of the hood, and the secondary pocket being formed by the flange and the subjacent wall of the hood.

3. A shallow-type downdraft diverter comprising a shallow dome-shaped hood having an aperture at the top adapted to communicate with a vent, a substantially circular conical diverter having its apex directed upwardly suspended from said hood co-axial therewith and disposed below said top aperture, the diameter of the diverter being substantially less than the diameter of said aperture, said diverter being located approximately midway between the top and lower edges of the hood, an annular collar depending from said diverter and spaced therefrom in co-axial relation, the upper edge of said collar being substantially level with the lower edge of the hood and the lower edge of the collar being below the lower edge of the hood, said collar being adapted to communicate with the upper end of a flue tube conveying products of combustion, and an annular flange depending from, and the upper edge thereof being in intimate and co-axial contact with said hood, the diameter of said flange being greater than the diameter of the lower edge of the hood and the lower edge of the flange being disposed above the upper edge of said collar, a passage for products of combustion being thereby formed by the annular collar, thence between the diverter and the flange and thence upwardly through the aperture in the top of the hood, and primary and secondary pockets for downdraft condition being formed, the primary downdraft pocket being defined by the flange and the superadjacent wall of the hood, and the secondary pocket being formed by the flange and the subjacent wall of the hood.

4. A downdraft diverter comprising a substantially dome-shaped outer hood having an undersurface and an outlet in the upper portion thereof, said hood being formed with an annular collar co-axial with said outlet defining a passage for products of combustion, said hood having its lower edge defined by a lip, an inner ring comprising a cylindrical wall having a substantially smaller diameter than the diameter of the lower lip of said hood and being formed with an inwardly directed upper peripheral flange, said flange being secured to the undersurface of said

5. A downdraft diverter comprising a substantially dome-shaped outer hood having an undersurface and an outlet in the upper portion thereof, said hood being formed with an annular collar co-axial with said outlet defining a passage for products of combustion, said hood having its lower edge defined by a lip, an inner ring comprising a cylindrical wall having a substantially smaller diameter than the diameter of the lower lip of said hood and being formed with an inwardly directed upper peripheral flange, said flange being secured to the undersurface of said

hood so that said inner ring is co-axial with said hood, said inner ring being defined by an outwardly directed lip at the lower periphery thereof substantially above the lower lip of said hood, a diverter cone having its apex pointed upwardly and being substantially smaller in diameter than the passage for exhaust gases through said peripheral collar and being positioned co-axial therewith in spaced relation from said hood and within the confines of the cylindrical wall of said inner ring, said cone being formed with a plurality of upwardly extending legs adapted to be secured to said hood to hold said diverter cone in position, and a mounting collar comprising a cylindrical wall positioned co-axially with said hood, said cone diverter being also formed with a plurality of downwardly extending legs adapted to be secured to said mounting collar, each of said legs being formed with an outwardly directed

ridge adapted to abut against the upper periphery of said mounting collar.

RICHARD E. JAMES.
